(57) **CLAIM**

The ornamental design for removable ash catcher for charcoal grill, as shown and described.

DESCRIPTION

FIG. 1 is a perspective view of a removable ash catcher for charcoal grill showing my new design;

FIG. 2 is a perspective view thereof, with the ash catcher removed from the charcoal grill;

FIG. 3 is a front elevational view thereof;

FIG. 4 is a rear elevational view thereof;

FIG. 5 is a left-side elevational view thereof;

FIG. 6 is a right side elevational view thereof;

FIG. 7 is a top plan view thereof; and,

FIG. 8 is a bottom plan view thereof.

The details shown in broken lines are for illustrative purposes only and form no part of the claimed design.
